UNITED STATES PATENT OFFICE.

FRANZ TRINKS, OF BRUNSWICK, GERMANY.

CALCULATING-MACHINE.

1,173,062.

Specification of Letters Patent. Patented Feb. 22, 1916.

Application filed April 23, 1914. Serial No. 833,986.

To all whom it may concern:

Be it known that I, FRANZ TRINKS, manufacturer, citizen of the Duchy of Brunswick, Empire of Germany, residing at 5 Brunswick, Germany, have invented certain new and useful Improvements in Calculating-Machines, of which the following is a specification.

My invention relates to improvements in 10 calculating machines, and more particularly in calculating machines in which the numeral wheels of the revolutions counting mechanism are provided with two series of numbers employed respectively for performing 15 additions and multiplications on the one hand and subtractions and divisions on the other hand, the numbers of the series being alternately arranged about the circumferences of the numeral wheels. In my United 20 States Patent No. 1,088,486 there is illustrated in Fig. 5 a suitable manner of arranging the numbers of both series. In the operation of the machine only one of the 25 series of numbers of each numeral wheel must be displayed through the peep hole while the other one must be covered, for which purpose a slide is provided to cover the peep holes of the numeral wheels and is formed with a single opening for displaying 30 or bringing into vision one number at a time, of each numeral wheel.

The object of the improvements is to provide automatic means whereby the slide for 35 the peep holes is set on the series of registering members which corresponds to the particular operation of the machine about to be performed, or, in other words, to the direction of rotation of the operating crank, when all of the rotating mechanism is shifted 40 to the zero position.

It is a further object of this invention to have the rotating counting mechanism shifted one step when passing from the zero point of the series of numbers provided for 45 addition and multiplication to the zero point of the series of numbers provided for subtraction and division. In calculating machines of the construction now in use a subsidiary tooth must be set by the hand of 50 the operator.

For the purpose of explaining clearly the invention, the same is shown in the accompanying drawings, in which the same reference numerals have been used in all the 55 views to indicate corresponding parts.

In said drawings, Figure 1, is a side view

of the calculating machine with the side wall of the casing removed and partly in section, Fig. 2, is a partial plan view of the machine with the cover of the casing partly removed, Fig. 3, is a side view similar to that shown in Fig. 1 but showing the parts in different positions, Figs. 4 to 7, are detail views of the machine shown in Figs. 1 to 3, and Figs. 8 and 9, are side views of the carrying mechanism which is preferably used in the machine shown in Figs. 1 to 7, the figures showing the parts in different positions.

Referring particularly to the drawings, 70 the calculating machine consists of setting disks 41 provided with a plurality of teeth 62 adapted to be shifted in a radial direction by means of cam disks 61. The setting disks are adapted to be rotated from a 75 machine operating crank 40, and when thus rotated the teeth 62, which have been shifted into operative positions, operate numeral wheels 60 of a registering mechanism. The said numeral wheels are mounted on a slide 80 85 64 adapted to be shifted in a direction parallel to the shaft 41' of the setting mechanism, and said wheels 60 are provided with resetting mechanism 65 and carrying means constructed in the form of hammers 59 adapted to operate the laterally shiftable teeth 58. Each of the setting disks 41, except the first one from the right, is provided with two laterally shiftable teeth, one for right hand and the other one for left 90 hand operation of the crank 40. The counting mechanism 66 may be provided on the slide 64 coaxially of the registering mechanism 60 and by means of which the number of the revolutions of the operating crank 95 40 is registered. The revolution counting mechanism 66 is adapted to be operated by means of a single tooth wheel 67 mounted on the shaft 41' and may have the construction shown in the United States Patent No. 100 1,040,059. However, it is to be understood that my present invention does not relate to this revolution counting mechanism, but to a revolution counting mechanism having 105 numeral wheels 3, which as shown, are located in the upper part of the machine above the setting mechanism 41, 61.

Through intermediate gear wheels 45, 46, and 47 the revolutions of the operating crank 40 are transmitted to a shaft 21 which 110 performs the same number of revolutions as said crank, and on which shaft 21 a single

tooth wheel 34 is mounted for axial displacement, as may be clearly seen in Figs. 6 and 6*. By means of the said single tooth wheel 34 and through the intermediary of intermediate gear wheels 42, 43, and 44 each rotation of the crank is registered on the numeral wheel 3, which cooperates with said single tooth according to the position of the latter, the said wheel 3 being turned forwardly or backwardly one step upon each rotation of the operating crank. Each of the numeral wheels 3 is connected with a governing disk 4 having a notch 5 adapted to be engaged by the beveled nose of a pawl 6. All the pawls are rigidly mounted to a shaft 7, which is mounted on a rocking lever 23. This arrangement of the pawls permits the same to be operated in unison with the movement of the lever 23 and to drop into engagement with the notches 5 of the disks 4, when said notches 5 are in position to receive the beveled noses of said pawls, which position is shown in Fig. 1. The dropping or downward movement of the pawls 6 may be caused by the influence of the spring pawl 38, see Fig. 7, connected with the pawls 6 and which will be hereinafter more fully described; however, it may be found desirable to have the pawls to drop by gravity. In the position of the pawls 6 as shown in Fig. 1, the zeros of the series of numbers corresponding to additions and multiplications are displayed through peep holes formed in a slide 2. Projecting from the pawl 6 cooperates with the numeral wheel of the lowermost order, is a pin 8 which operates a lever 9 journaled in the side wall of the machine casing said lever 9 being connected by a link 10 with a rocking lever 14 mounted on the shaft 42' of the intermediate gear wheels 42 and carrying a gear wheel 11. When the pawl 6 moves downwardly, the pin 8 rocks the lever 9, the link 10 and which, in turn, moves the lever 14 downwardly, so that the gear wheel 11 is shifted bodily into the path of two teeth 12 and 13 which take part in the rotation of the machine operating crank 40, this position of the parts being shown in Fig. 1. The gear wheel 11 is in mesh with the intermediate gear wheel 42, so that the revolutions counting mechanism 3 can be shifted one step by means of either one of the teeth 12 or 13. In order that during this shifting operation the lever 14 may not be rocked with the gear wheel 11 out of position for engagement with the teeth 12 or 13, a spring actuated locking pawl 15 is provided and formed with two shoulders adapted to engage with an arm 14' of the lever 14, respectively, in its rocked and normal positions. Projecting from the arm 14' of the lever 14, is a pin 16 adapted to rock a bell crank lever 17, 17', mounted on a shaft 18, clockwise when the gear wheel 11 is rocked into the operative position

shown in Fig. 1. The shaft 21 carries a transverse pin 19 on which a finger 20 has a rocking support. When the lever 17 is rocked its arm 17' sets the finger 20 in erect position, and when the shaft 21 is turned to the right for performing additions or multiplications the erected finger 20 strikes against a pawl 22 pivoted to the rocking lever 23, the latter being mounted on a shaft 24, and which, when rocked upward, shifts the locking pawl 15 into non-locking position by acting on a pin 25 connected with the said pawl. Thereby the gear wheel 11 is moved into the inoperative position shown in Fig. 3, and the lower arm 17' of the lever 17 releases the finger 20 so as to permit the same to be returned into normal position by suitable means such as a spring (not shown). Therefore the teeth 12 and 13 and the finger 20 are inoperative during the following addition or multiplication, so that they can not affect the result of the calculation registered on the revolution counting mechanism 3.

The carrying mechanism is shown in Figs. 1, 2, 8, and 9. As shown each of the intermediate gear wheels 43, which are constantly in engagement with the numeral wheels 3, is equipped with a pin 48. When one of the numeral wheels 3 passes from its "zero" position to its "nine" position or vice versa the corresponding pin 48 acts on a co-operating rocking lever 49 in such a way as to rock a gear wheel 50 which is mounted on the lever 49 and which is always in engagement with the intermediate gear wheel 42 of the next higher order. Thereby the gear wheel 50 is shifted into the path of teeth 51 which take part in the rotation of the shaft 41' of the machine crank, so that when rotating the setting disks 41 one of the teeth 51 engages with the gear wheel 50 and effects the carrying operation through the intermediate gear wheels 42, 43, 44. The gear wheel 50 is held in its rocked position by means of a locking pawl 53 which is shifted by a spring 52 below the elevated right hand end of the lever 49. At the end of the carrying operation the locking pawl 53 is returned into initial position by means of a bell crank lever 56 which rocks an arm 55 connected with the shaft 54 of the locking pawl in the direction of the arrow 68 shown in Fig. 8. For operating the bell crank lever 56 a cam disk 57 is provided which takes part in the rotation of the setting mechanism 41. After the locking pawl 53 has been rocked into non-locking position, a spring, for example the spring 52, rocks the lever 49 downwardly and in contact with the lower shoulder of the pawl 53. Thus all the parts are returned into normal positions, and the transmission wheel 50 is out of the path of the teeth 51. When the numeral wheel passes again from its nine position to its zero position, 130

or vice versa, the same operation is repeated.

In order that each of the pawls 53 may be rocked beneath the coöperating lever 49 independently of the other levers 49, the said pawls are coupled to their shaft 54 by pin and slot connections which permit slight rocking movements of the pawls relatively to said shaft, which movements are sufficient to permit the pawls to move into locking engagement with the coöperating levers 49.

If it is desired to perform a subtraction or division after the registering mechanism has been reset all the numeral wheels 3 must be rotated so far that the pins 48, which start the carrying operation are moved from the front sides of the levers 49 to the rear sides thereof because, otherwise, the first rotation of a numeral wheel 3 caused by the single tooth 34 would result in a carrying operation, while such a carrying operation should take place after ten operations of the crank of the machine. Furthermore, the slide 2 which is formed with the peep holes must be set in such a way that instead of the zeros corresponding to the additions and multiplications the zeros corresponding to the subtractions and divisions are displayed through the peep holes. In my improved machine these operations, to wit, the rotation of all the numeral wheels and the setting of the slide formed with the peep holes are automatically performed, without operation of any of the parts by hand. For this purpose the following mechanism is provided: In explaining the mechanism I shall start from the normal position of the parts shown in Fig. 1, in which, in the zero position of the numeral wheels 3, the noses of all the pawls 6 engage in the notches 5 of governing disks 4 and the wheel 11 is in the path of the teeth 12 and 13. When rotating the shaft 21 to the left or in the direction of the arrow *w* shown in Fig. 1 for performing a division or subtraction, the erected finger 20 strikes against a nose 26 of the lever 23 and rocks the said lever about its shaft 24 in the direction of the arrow *x* shown in Fig. 1. Thereby the pawl 6 which is connected with the opposite end of the lever 23 is moved in the direction of the arrow *y* shown in Fig. 1 and into the position shown in Fig. 3. The lever 23 is adapted to be locked in its end positions by a locking pawl 27 adapted to engage in either one of notches 28 and 29 of the lever 23. By shifting the pawl 6 the slide 2 which is provided with the peep holes and has a rocking support on the shaft 1 is lifted, an upwardly curved arm 30 connected with the said slide being forced downwardly by the rearward movement of the shaft 7 carrying the pawls 6. By this movement or operation of the peep hole slide 2, the number which originally was dis-

played through the peep holes and which corresponds to additions and multiplications is covered, and another number is displayed which belongs to the series of numbers corresponding to subtractions and divisions. While the shaft 21 is thus being rotated the pawls 22 are not engaged by the fingers 20, so that the pawl 15 is not rocked. Therefore, the gear wheel 11 remains at first in the operative position shown in Fig. 1 in which the tooth 13 can perform a carrying operation through the intermediary of the gear wheel 11 and the intermediate gear wheels 42, 43, and 44. This carrying operation is transmitted through the pins 48, the levers 49, the gear wheels 50, and the teeth 51 (Figs. 2 and 8) to all the other numeral wheels 3, which is necessary in order that the zeros of the series of numbers corresponding to the division are displayed through the peep holes, and in order to bring the carrying means, that is the pins 48 (Figs. 2 and 8,) which are common to both series of numbers, to the opposite sides of the levers 49, so that carrying is performed in the correct position when the series of numbers corresponding to the division are used, the numeral wheel 3 is advanced by the single tooth 34 one step for each revolution of the crank of the machine, in the same way as when performing additions and multiplications.

When turning the crank clockwise the finger 20 rocks the lever 23 through the intermediary of the pawl 22 into the position shown in Fig. 1, whereby the peep hole slide 2 which is under the action of the spring 31, is turned into the position corresponding to the addition and multiplication.

In my improved machine the driving member 34, connected with the machine crank 41' and provided for registering the number of rotations of the crank, must come into operation as nearly as possible immediately after starting the operation of the crank 41'. In order that this be the case in both directions of rotation of the crank suitable means are provided, such as those shown in Figs. 6 and 6*. To the shaft 21 a sleeve 32 is slidably connected which is provided with two teeth 34 actuated by a common spring 33. These teeth 34 are so supported by fixed projections 35 of the sleeve 32 that both teeth can be rocked inwardly but not outwardly. If the shaft is turned in the direction of the arrow *z*, the tooth 34 which is located at the right is inoperative, because it is tilted into the position shown in dotted lines as soon as it is engaged by the transmission gear wheel 42 cooperating therewith, while the tooth 34 which is located at the left is operative immediately after rotation of the shaft 21 has been started. When rotation of the crank shaft 130

takes place in the opposite direction, the tooth 34 which is located at the right is operative, while the left hand tooth yields to the gearing.

5 In order that when shifting the pawl 6 in the direction of the arrow *y* shown in Fig. 1, the numeral wheels 3 may not be rotated the mechanism shown in Fig. 7 is provided. This mechanism has, also, the function to 10 lift the beveled noses of the pawls 6 out of frictional engagement with the circumferential notches 5 of the disks 4. For this purpose, one of the pawls whose nose 6 is connected by a rod 37 with a spring actuated 15 pawl 38 in the normal position of the crank, engages in a notch of a disk 39 rigidly connected with the shaft 21. Therefore, when, the crank is rotated either to the right or to the left the pawls 6 are lifted by the disk 20 39, the pawl 38, and the rod 37 to such an extent that the disks 3 and 4 can not be carried along when the pawls 6 move in the direction of the arrow *y* shown in Fig. 1.

For resetting the revolutions counting 25 mechanism 3 a wing nut 69 is provided which is shown in Fig. 2.

The operation of the present invention may be described as follows: When the numeral wheels 3 are reset by the turning 30 of the wing nut 69, the crank handle 40 may be turned in a direction corresponding to the work to be done by the machine; that is, the handle may be turned to the left of its position shown in Fig. 1 when it is desired to add or multiply, or it may be turned to the right when it is desired to subtract or divide. This preliminary movement of the handle shifts the slide 2 to such a position that the proper numerals will be exposed 35 or displayed through its peep openings. Said shifting is effected in the following manner: When it is desired to add or multiply, the crank handle 40 is moved to the left of its position shown in Fig. 1, therefore 40 by rotating with it the disk 41 and the gear 45, which rotates the teeth 34 clockwise through the intermediate gears 46 and 47. The teeth 34 engage upon each rotation thereof with the gear 42 which rotates the 45 same one step to effect the consequent step-by-step rotating movement of the numeral disk 3 and the notched disk 4, through the intermediate gear 43. This rotation of the disks 4 will bring the notch 5 thereof into 50 position to be engaged by the pawls 6 which will be moved downwardly by the influence of the spring pawl 38 into said notch. Upon the downward movement of the pawl 6, the projection 8 engages with the lever 9, thus 55 moving the same upon its pivot downwardly to actuate the rocking lever 14 carrying the gear 11 meshing with the gear 42, the gear 11 being moved in the path of the projections 12 and 13 of the disk 41. At this 60 point, the machine is now positioned to

register and as the disk 41 rotates the teeth 12 or 13 will engage with the disk 11 to impart a step-by-step rotating movement to the latter, which, in, turn, imparts said movement to the gear 44, which will rotate 70 the numeral wheel 3 upon each rotation of the disk 41 and thus cause the counting mechanism to register, as will be clearly understood. The gear 11 is held in the path of the teeth 12 and 13 during the counting 75 operation of the machine by the locking pawl 15 which is operated in the following manner: When the said gear is moved downwardly, the rear end of the rocking lever 14 is moved upwardly in a direction 80 indicated by the arrow *x*, Fig. 1, which rear end carries a pin 16 adapted to engage with the upper end of the bell crank lever 17, which latter engagement will move the end 17' of the bell crank lever in the position 85 shown in Fig. 1 to erect the finger 20 to effect the engagement of the latter with the pawl 22. When the pawl 22 is engaged by the finger 20, the same is moved upwardly and engages with the pin 25 of the pawl 90 15 and moves the same rearwardly against the tension of its spring so that the rear end of the rocking lever 14 will rest in the upper shoulder of the pawl 15, whereby the lever 14 is locked in the position shown in Fig. 1 95 and the gear 11 is held in the path of the teeth 12 and 13. The above operation will permit an addition or multiplication operation of the machine and the slide 2 will be held in position to display through its peep 100 hole the proper series of numerals for such operation.

When it is desired to use the machine for subtracting and dividing, the numeral disks 3 are reset by the wing nut 69 and the crank handle 40 is rotated to the right or anti-clockwise. This rotation of the crank handle will rotate the shaft 21 in the direction of the arrow *w*, Fig. 1, and the finger 20 will engage with the projection 26 of the rocking arm 23 which will rotate the arm 23 in the direction of the arrow *x*, and, in consequence, moves the shaft 7 in the direction of the arrow *y*. The shaft 7 carries with it the pawls 6 which are raised by this movement of the shaft from the notches 5 and disks 4. The shaft 7, when moved in the direction of the arrow *y*, engages with the upwardly and rearwardly extended arm 30 and moves the same downwardly against the tension of the expansion spring 31, and consequently, effects a shifting of the slide 2 whereby suitable subtraction and division series of numbers on the disks 3 are displayed through the peep hole of said slide. 120 By turning the crank handle clockwise, the finger 20 will engage with the pawl 22 to so operate the lever 23 upon its pivot 24 as to cause the same to assume the position shown in Fig. 1, whereupon the spring 31 130

exerts its tension upon the arm 30 and causes the slide 2 to be moved into position to display the addition and multiplication numerals of the numeral wheel 3.

5. I claim herein as my invention:

1. In a calculating machine, the combination with a revolutions counting mechanism comprising numeral wheels having two series of alternately arranged numbers, and 10 normally inoperative means to rock all the numeral wheels, of normally locked movable members adapted to be released when all the numeral wheels are in corresponding positions and when released to throw said rocking means into operation, and means to return the movable members into locked position.

2. In a calculating machine, the combination with a revolutions counting mechanism 20 comprising notched numeral wheels having two series of alternately arranged numbers, and normally inoperative means to rock all the numeral wheels, of pawls adapted to engage in the notches of the numeral wheels 25 when the latter are in corresponding positions, means controlled by said pawls to throw said rocking means into operation, and means to return the pawls into locked position.

30. 3. In a calculating machine, the combination with a revolutions counting mechanism comprising numeral wheels having two series of alternately arranged numbers, and normally inoperative means to rock all the 35 numeral wheels, of normally locked movable members adapted to be released when all the numeral wheels are in corresponding positions and when released to throw said rocking means into operation, means to return 40 the movable members into locked position, means to lock the rocking means in operative position, and means operative after the operation of the rocking means to throw said locking means for the rocking means 45 out of operation.

4. In a calculating machine, the combination with the registering mechanism, the setting mechanism, and operating means therefor, of a revolutions counting mechanism 50 comprising numeral wheels having two series of alternately arranged numbers, means to display the numbers of either one of the series of numbers on the numeral wheels, and means controlled by said operating 55 means when changing the direction of operation of the same to shift the displaying means from displaying position relatively to one series of numbers into displaying position relatively to the other series of numbers.

60. 5. In a calculating machine, the combination with the registering mechanism, the setting mechanism, and operating means therefor, of revolutions counting mechanism 65 comprising numeral wheels having two

series of alternately arranged numbers, a normally locked movable member adapted to be released when all the numeral wheels are in corresponding positions, means to display the numbers of either one of the series of numbers on the numeral wheels, normally inoperative means controlled by said operating means when changing the direction of operation of the same to shift the displaying means from displaying position 70 relatively to one series of numbers into displaying position relatively to the other series of numbers, and means controlled by said movable member when being released to throw said normally inoperative means 75 into operation.

6. In a calculating machine, the combination with a revolutions counting mechanism comprising notched numeral wheels having two series of alternately arranged numbers, 80 means to display the numbers of either one of the series of numbers on the numeral wheels, pawls adapted to engage in the notches of the numeral wheels when the latter are in corresponding positions, and an 85 operative connection between said pawls and displaying means adapted to shift the displaying means from displaying position relatively to one series of numbers into displaying position relatively to the other series 90 of numbers.

7. In a calculating machine, the combination with the registering mechanism, the setting mechanism, operating means therefor, and a revolutions counting mechanism comprising notched numeral wheels having two series of alternately arranged numbers, of means to display the numbers of either one of the series of numbers on the numeral wheels, when the latter are in corresponding 100 positions, normally inoperative means controlled by said operating means when changing the direction of operation of the same to shift the displaying means from displaying position relatively to one series of numbers 105 into displaying position relatively to the other series of numbers, and means controlled by said pawls when being released to throw said normally inoperative means into operation.

115. 8. In a calculating machine, the combination with the registering mechanism, the setting mechanism, and operating means therefor, of revolutions counting mechanism comprising numeral wheels having two series of alternately arranged numbers, a normally locked movable member adapted to be released when all the numeral wheels are in corresponding positions, a slide adapted to display the numbers of either one of the series of numbers on the numeral wheels and having an operating arm, a rocker engaging said arm, normally inoperative means controlled by said operating means when changing the direction of operation of the same to 120

125

130

- rock said rocker so as to shift the slide from displaying position relatively to one series of numbers into displaying position relatively to the other series of numbers, and means controlled by said movable member when being released to throw said normally inoperative means into operation.
9. In a calculating machine, the combination with the registering mechanism, the setting mechanism, and operating means therefor, of revolutions counting mechanism comprising two series of alternately arranged numbers, and carrying means therefor, a normally inoperative finger taking part in the operation of the operating means and adapted to move said carrying mechanism into inoperative position when being operated in one direction; means controlled by said carrying mechanism to set said finger in operative position, means to display either one of the series of numbers, and mechanism controlled by said finger and operative when turning the same in a direction opposite to the direction in which it moves the carrying mechanism into inoperative position to shift said displaying means from displaying position relatively to one of said series of numbers into displaying position relatively to the other one of said series of numbers.
10. In a calculating machine, the combination with the registering mechanism, the setting mechanism, operating means therefor, and a revolutions counting mechanism comprising notched numeral wheels having two series of alternately arranged numbers, and normally inoperative means to rock all the numeral wheels, of pawls adapted to engage in the notches of the numeral wheels when the latter are in corresponding positions, means controlled by said pawls to throw said rocking means into operation, means to return the pawls into locked position, and a cam taking part in the operation of said operating means and adapted to lift the said pawls out of engagement with the notches while the operating means are in operation.
- In testimony whereof I have hereunto set my hand in presence of two subscribing witnesses.

FRANZ TRINKS.
